UNITED STATES PATENT OFFICE

EDWARD J. HALE, OF MINCO, OKLAHOMA

GRAIN-HEADING MACHINE

Application filed June 27, 1928. Serial No. 288,772.

This invention relates to a machine for heading grain such as cane, Kaffir-corn, maize and the like.

It is aimed to provide a generally efficient, 5 comparatively inexpensive and durable machine adapted to receive cut unthreshed grain, remove the kernels therefrom and load the same onto a wagon or receptacle forming part of the machine, and at the same time dis- 10 charge the straw onto the ground, as the machine travels thereover, for use as fertilizer.

It is particularly aimed to provide a machine of this character having a novel means 15 at the front to receive and convey the grain to the heading mechanism, which means is adjustable as to height according to conditions of use.

Another object is to provide a novel construction wherein the machine proper is adjustable as to height and such machine and the wagon or vehicle are relatively movable longitudinally to take up slack in operating 20 parts especially incidental to the aforesaid 25 adjustment.

Still another object is to provide a novel construction of heading mechanism and means for conveying the grain kernels to a wagon body or receptacle.

Various additional objects and advantages 30 will be pointed out or become apparent from a consideration of the description following taken in connection with accompanying drawings illustrating an operative embodiment.

Figure 1 is a top plan view of the improved grain heading machine;

Figure 19 is a sectional detail on a plane indicated by the line 19-19 of Figure 18;

Figure 20 is a sectional detail on a plane indicated by the line 20-20 of Figure 7; and 75

Figures 21 and 22 are sectional details on planes indicated by the lines 21-21 and 22-22, respectively, of Figure 20.

Referring specifically to the drawings, the parts generally are supported by a suitable 80 mobile machine frame 1, a wagon or vehicle frame 2 and an auxiliary frame 3 rigid with wagon frame 1, each frame being of a fabricated or skeleton form. Fastened to

frame 2 is a transverse axle 3^a having ground 85 wheels 4 and 5 journaled thereon. Such fastening of the frames is adjustable to enable

frames 1 and 2 to have slight relative longitudinal adjustment for a purpose hereinafter described, and to this end, axle 3^a has an arm

6 rigid therewith which may be fastened by removable bolts 7 in selected openings 8 provided through bars 9 of frame 3. Wagon

frame 2 carries a relatively large C-shaped 90 plate or bracket 10 at the inner side thereof provided with elongated slots 11 there-

through. Saddles 12 rigid with the machine frame surround and are slidably relatively to the bracket 10. Vertically disposed guide

rods 13 rise from frame 3 and are disposed 95 100

through certain of the slots 11. Screw rods 14 rigid with frame 1, depend through the remaining slots 11 and are engaged by nuts 14^a which rest on top of the saddles. Conventional ratchet wrenches 14^b may be attached to the nuts 14^a to operate them. As the nuts 14^a rest on the saddles, the height of the nuts governs the vertical adjustment of the machine frame 1. Wedge bolts 14^c 5 may be carried by the saddles to bind against the rods 13 to assist the screw rods 14 in supporting the frame 1. Support of the apparatus by the said wheels is supplemented by a smaller wheel or colter 14^d journaled in 10 a bracket 15 of a vertically disposed rod 16 which is slidably mounted in arms of a bracket 17 fastened to a part of the frame 1. An expansive coil spring 18 surrounds the rod 16, abutting one arm of the bracket 17 15 and a stop 19 on said rod, thus yieldingly maintaining the roller or wheel 14^d in engagement with the ground.

As best shown in Figure 3, the right hand side or frame 2 of the machine constitutes a wagon since it has a wagon body or receptacle 20 supported by suitable bolsters 21 from the said axle 3^a. A draft animal or a tractor (not shown) is adapted to be hitched in any suitable manner to the wagon as at a tongue 25 or pole 22, to draw the same over the ground and thereby impart rotation especially to the wheel 5 which is used therefore as the power wheel.

The grain header mechanism is generally 30 designated A and appropriately mounted on the frame 1. Such mechanism will be specifically described hereinafter.

In order to supply the unthreshed grain to the header mechanism A, two spaced simultaneously operable feeding devices generally 35 designated B are employed. These devices consist of metallic or other frames of a skeleton nature primarily of two rigidly joined generally triangular frame elements 24 as best seen in Figures 2 and 3. These elements 40 mount transverse shafts 25 on which sprocket wheels 26 are journaled and which are traversed by endless conveyor belts or chains 27 adapted to move upwardly and rearwardly 45 and which are provided with flights 28. Chains 27 also traverse sprocket wheels 26' 50 mounted on frame 1.

The frame 1 has a rock shaft 29 journaled transversely thereof, which is provided with 55 a plurality of downwardly and rearwardly extending cranks 30. Pivoted to certain of the cranks 30 as at 31 are links 32 which extend forwardly and are pivoted at 33 to brackets 34 fastened to the frames 24. The 60 frames 24 at 35 are pivoted or hinged on horizontal axes to the frame 1. Frame 1 has a platform 36 provided with a bracket 37 to which a lever 38 is pivoted. Said lever has a depending portion 39 to which a link 40 is 65 pivoted which is also pivoted to the remain-

ing crank 30. Pivoted as at 41 to the link 40, midway of its ends, is a link 42 which is pivoted to one of the frames 24 as at 43.

Since all of the frames 24 have connections with the rock shaft 29, the same are movable 70 in unison to different adjusted positions from the axis 35 and are adapted to be fastened in such positions through the engagement of a latch 43 of lever 38 with a toothed rack 44 on the platform 36. The frames 24 have 75 ground engaging shoes 45 pivoted thereto as at 46 and such frames also have plates 47 pivoted thereto at 48 and provided with elongated slots 49 through which bolts 50 pass to guide them for sliding movement. Incidental to the turning of the frames 24 about the axis 35, the said plates or slides 47 will correspondingly move.

The sprockets 23', while located substantially within the frames 24, are rigid on 80 shafts 52 and 53, such shafts being journaled in bearings 54 and 55, respectively, on the frame 1. Mounted on the shaft 52 is a pinion 54 with which a pinion 55' meshes carried by a shaft 56, journaled in bearings 57 on the frame 1. Keyed to the shaft 56 is a sprocket wheel 57' over which a sprocket chain 58 is trained and which is housed within a trough or protective casing 59 on the frame 1. Sprocket chain 58 is also trained over a 85 sprocket wheel 60 at the rear of the machine keyed to a transverse shaft 61 journaled in suitable bearings 62'. The shaft 61 is adapted to be driven by a sprocket chain 62 trained over a sprocket wheel 63 clamped to the 90 power wheel 5. Such sprocket chain 62 also passes over a sprocket wheel 64 normally loose on the shaft 61 but adapted to be arranged in driving relation therewith by means of a conventional clutch 65 operable 95 through the medium of a lever 66.

The shaft 53 has a sprocket 67 keyed thereon which drives a suitable conveyor 68 trained thereover and which also is trained over a sprocket wheel 70 keyed to a transverse shaft 71 parallel to the shaft 61. The conveyor 68 is located within a trough 72.

As the machine traverses a field, the unthreshed grain is placed by a workman transversely of the conveyors 27 and being engaged by the flights 28 is moved upwardly. A workman stands on the platform 36 and as the grain accumulates at the upper extremity of the frames 24, the workman grasps the same in bundles, and arranges it vertically, with the grain heads or kernels uppermost and with the cut ends depending between the frames 24 into slots 75 and moves rearwardly against a deflector plate 76 on the frame 1 so as to be received into anyone of a series of notches 77 of a plate 78.

As the vertical bundles of the unthreshed grain thus move inwardly, it is gripped between a fixed longitudinal bar 79 on the frame 10 and a movable longitudinal bar 80

on such frame, the bar 80 being laterally yieldable or movable as best shown in Figure 9, since it is carried by brackets 81 pivotally mounted on the frame at 82 and has guide rods 83 pivoted thereto at 84 and slideable through supports or guides as at 85. Expansive coil springs 86 engage such guides 85 and fixed elements 87 on the rods 83. Thus the springs 86 urge the bar 80 into engagement with or toward the fixed bar 79 whereby the unthreshed grain is gripped. At the same time, the unthreshed grain, thus gripped, is conveyed rearwardly or longitudinally of the machine by conveyer chains 88 and 89, arranged one above the other, and each provided with laterally extending lugs or flights 90 to engage such vertical bundles of unthreshed grain to forcibly slide it forwardly. Near the start of such sliding movement, a portion of the straw of such grain is severed by the contact thereof with a rotatable knife 91. As the unthreshed grain is thus unsupported or gripped from below, and since at this stage, the lower ends are gripped between threshing or heading rolls 92 and 93, the unthreshed grain is pulled downwardly and inwardly into substantial parallelism with the axes of the rollers 92 and 93 whereby, kernels are removed as the grain is pulled between the plates 79 and 80. The roller 92 is longitudinally grooved or corrugated to provide pockets 94 and the roller 93 is spirally corrugated or fluted as at 95. As a result, as the grain passes downwardly between the rolls 92 and 93 the remaining kernels of grain are removed, lodging in the pockets 94 and falling therefrom through the rotation of roller 92 into a main collecting trough 96 having a conveyer 97 disposed therein. A specific form of the roller 93 aids in somewhat crushing the straw to facilitate rotting thereof for fertilizer purposes and such straw with the grain completely threshed therefrom, as it passes between the rolls 92 and 93, falls between rolls 98 and 99, below the aforesaid rolls, passing between such rolls and thence out of the machine through an opening 100 in the bottom thereof, where it deposits on the ground for use as fertilizer.

Should any of the straw remain upstanding near the rear ends of the rolls, it will be engaged by a hook 101 suitably fastened on the machine and its movement arrested so that it will be severed or cut by a rotatable knife 102.

A resilient finger 103 may be arranged opposite the guide plate 76 and be fastened as at 104 to the frame 10, to aid in gripping the bundles of unthreshed grain as the same are moved backwardly or rearwardly by the disks 78 into engagement with bars 79 and 80.

The heading mechanism A is covered by a suitable hood 105, part of which 106, is a

closure hinged in place at 107, permitting access to the heading mechanism. The trough 96 together with adjacent elements is also closed and protected by a hood as at 108, having a door or closure 109 provided therethrough.

The hood 105 constitutes a guide whereby grain which is headed as the straw is drawn between the bars 79 and 80, falls and is guided into the previously mentioned trough 72 and conveyed rearwardly by the conveyer 68 which conveys the grain rearwardly into a trough 110 which is in communication with the trough 72 at the rear of the machine and transversely thereof. Such trough 110 has a conveyer 111 therein to move the grain into a trough 112 which is the main receiving trough and which has the main conveyer 113 located therein.

The rolls 93 and 98 are mounted so that they may yield away from the rolls 92 and 99, respectively, in the presence of undue bulk. They are yieldably mounted, however, and always urge toward said rolls 92 and 99, respectively. Said rolls 93 and 98 are mounted rigidly on shafts 93^a and 98^a respectively. Said shafts are journaled in suitable bearings 114, which are transversely slideable in ways 115 provided in adjacent bars 116 forming part of the frame 1 and located beneath the hood 105. Such bearings 114 are provided with guide rods 116^a slideably mounted through guides 117 on the brackets 116. Expansive coil springs 118 surround the rods 116 and at one end abut the bearings 114 and at the other end abut the guides or blocks 117. The rolls 92 and 99 are rigid on shafts 92^a and 99^a, respectively, suitably journaled in bearings 119 on or forming part of the frame 1.

The transverse shaft 61 through the medium of a suitable transmission mechanism conventionally shown as at C, drives the aforesaid parallel shaft 71, which as previously stated drives the sprocket 70 in order to operate the conveyer 68. Said shaft 71 has a bevel gear wheel 121 keyed thereto which meshes with a bevel gear wheel 122 on a shaft 123. Shaft 123 has a gear wheel 124 keyed thereto which meshes with a gear wheel 125 keyed to the shaft 99^a on which a bevel gear wheel 127 is also keyed and is in mesh with a bevel gear wheel 128 carried by a vertical shaft 129 which drives the cutter 102. It will be realized that as previously stated, the shaft 99^a drives the roll 99.

On said shaft 99^a a sprocket wheel 130 is keyed over which a sprocket chain 131 passes and which in turn traverses a sprocket wheel 132 carried by shaft 92^a whereby the latter and the roll 92 are driven. Shaft 99^a has a bevel gear wheel 133 keyed thereon which meshes with a bevel gear wheel 134 carried by a vertically disposed shaft 135 journaled in suitable bearings 136 on the frame 1. Shaft 135

135 has a sprocket wheel 136 thereon traversed by the conveyer 88 whereby the latter is driven.

Conveyer 88 also traverses a sprocket wheel 137 carried by a vertical shaft 138 suitably journaled in the frame 1 and on which shaft the plate or disk 78 is fastened so as to be rotated. On the shaft 138 a gear wheel 139 is keyed which is traversed by the lower conveyer 89, the latter also traversing an idler sprocket 140 mounted on a vertical shaft 141 suitably journaled in the machine.

The cutter 91 is carried by a vertical shaft 142 supported in suitable bearings 143. On shaft 142 a bevel gear wheel 144 is keyed which is in mesh with a bevel gear wheel 145 carried by the shaft 99^a and roll 99. Thus the shaft 99^a and roll 99 drive the cutter 91.

On the shaft 123, a sprocket wheel 150 is keyed which is traversed by a sprocket chain 151 which also passes over a sprocket wheel 152 keyed on the shaft 98^a so as to rotate the roll 98. Associated with the chain 151 is a conventional automatically operated belt 153. Traversing a sprocket wheel 154 on the shaft 98^a is a sprocket chain 155 which also traverses a sprocket wheel 156 keyed to the shaft 93^a whereby the roll 93 is operated. A conventional automatically operating belt tightener 157 coacts with the sprocket chain 155.

In order to drive the conveyer 111, a bevel gear wheel 160 is keyed to shaft 71 and meshes with a bevel gear wheel 161 on a shaft 162 having a sprocket 163 thereon traversed by the sprocket chain 111. At the other end, sprocket chain 111 traverses an idler sprocket wheel 164 mounted in any appropriate manner.

The main conveyer 113 traverses an idler sprocket wheel 166 suitably mounted in the rear end thereof and such conveyer also traverses a sprocket wheel 167 keyed to the shaft 56 whereby such main conveyer is driven.

The main conveyer trough 96 is arranged to discharge at its forward end into an inclined chute 170 suitably fastened at the front of the machine. Operable within the trough 170 is an elevator or conveyer chain 171, having flights 172 thereon whereby the grain is elevated and discharged into a discharge chute 173 mounted on the trough 170, resting against the bracket 174 but preferably being pivoted as at 175 so that the same may be thrown back against the trough 170 when not discharging. Discharge chute 173 conveys the grain into the wagon body 20. The conveyer 171 is mounted on an idler sprocket wheel 176 at its lower end, suitably mounted within the trough 170. At its upper end, such chain 171 is trained over the sprocket 177 keyed to a shaft 178 journaled in wall of the trough 170 and extending exteriorly thereof and there having a sprocket wheel 179 keyed thereto. Chain 179^a traverses a sprocket

wheel 180 carried by a short shaft 181 suitably journaled on the frame of the machine. On shaft 181, a bevel gear wheel 182 is keyed which meshes with a bevel gear wheel 183 keyed on the shaft 56 so as to be driven from the latter.

Especially when the main drive chain 62 becomes slack through the relative adjustment of the machine frame 1 relative to the vehicle body or frame 2, such bodies or frames are adapted to be slid relatively as accommodated by the slots 11 and rods 13 passing therethrough. Before accomplishing this relative sliding or shifting movement, it is to be understood that bolts 7 are removed. A bar or link 185 is connected to the saddles and a link 186 pivoted thereto and to an operating lever 187 which is fulcrumed at 188 on the bracket 10. Lever 187 may be fastened in adjusted position by latch means 188 coacting with a toothed segment 189. By reason of the construction described, as lever 187 is operated, the saddles and bracket 10 will move relatively, resulting in relative movement of the machine frame 1 and the vehicle frame 2, thus taking up the slack in such main drive chain, after which the bolts 7 are applied to the proper openings in the arm 6 and bars 9.

The main drive wheel is preferably equipped with traction teeth or spurs 190.

To briefly recapitulate the operation heretofore specifically set forth in connection with the description of the parts, the machine is driven or moved over the field during which action the workman placed cut and unthreshed grain in bundles transversely of the conveyers 27, and in engagement with the flights 28 whereby the same is elevated to the top of the frames 24, accumulating at such points and being removed by a workman stationed on the platform or adjacent parts 36. Such bundles are turned by hand to a vertical position with the butt ends down and then passed while held vertically through the space 75, guided by the deflector or guides 76 into engagement with adjacent pockets 78 of the disk 77. Since the disk 78 bears frictionally against the adjacent guides, the bundles are frictionally held so that they are conveyed rearwardly by the lugs 90 of the conveyers 88 and 89. As the upstanding unthreshed grain travels rearwardly, the lower portions of the straw are severed through the action of the cutter 91 whereupon the action of the rolls 92 and 93 draws the grain to a horizontal position between them. The cut straw falls to the ground through the openings 100 and such drawing downwardly of the grain causes a large percentage of the kernels or heads to be removed by the coaction of the plates or bars 79 and 80 therewith. The rolls 93 and 92 thresh the remainder of the heads or kernels from the grain. The heads threshed by the bars 79 and 80 are guided by the hood 105 into the trough 72 where it is conveyed

125

130

rearwardly by the conveyer 68 into the trough 110 and thence conveyed laterally by the conveyer 111 therein into the trough 112 so that the main conveyer 61 moves it forwardly into the inclined trough 170 for elevation by the associated elevator therein and discharged into and through the chute 173 into the body 20. At the same time, such grain heads or kernels as it passes through the main conveyer trough is met by the grain discharge thereinto by the roll 92.

The frames 24 may be adjusted as to height at desired times through adjustment of the lever 38 and mechanism previously specifically traced. Also the frame 1 and parts mounted thereon may be adjusted vertically when desired through the adjustment of the nuts 14^a under the action of the wrenches 14^b. Also the main drive chain 20 may be tightened when necessary upon removing the bolts 7 and adjusting the lever 187.

Various changes may be resorted to provided they fall within the spirit and scope of the invention.

I claim as my invention:—

1. A machine of the class described having grain heading mechanism, means to grip the grain, said heading mechanism being designed to move the grain relative to the first mentioned means so that the latter will partially head the grain.

2. A machine of the class described having grain heading mechanism, means to grip the grain, said heading mechanism being designed to move the grain relative to the first mentioned means so that the latter will partially head the grain, a hood over said heading mechanism, conveyer means, and said hood serving to direct the grain headed by the first mentioned means into said conveyer.

3. A machine of the class described having grain heading mechanism, means to grip the grain, said heading mechanism being designed to move the grain relative to the first mentioned means so that the latter will partially head the grain, a hood over said heading mechanism, conveyer means, and said hood serving to direct the grain headed by the first mentioned means into said conveyer, the conveyer to receive headed grain from said mechanism, and a conveyer to transfer grain from the first conveyer to the last mentioned conveyer whereby the grain may reach a common source of discharge.

4. A machine of the class described having heading rolls, a fixed and a movable stripper bar, this stripper bar being adapted to receive unthreshed grain in a vertical position, a disk having a notch to initially receive the grain and start travel thereof, a conveyer having projections engageable with the grain to assist travel thereof, and a cutter to remove the lower ends of the straw as the grain is

conveyed by said conveyer, and threshing rolls to receive the grain in a substantially horizontal position.

5. A machine of the class described having heading rolls, a fixed and a movable stripper bar, this stripper bar being adapted to receive unthreshed grain in a vertical position, a disk having a notch to initially receive the grain and start travel thereof, a conveyer having projections engageable with the grain to assist travel thereof, and a cutter to remove the lower ends of the straw as the grain is conveyed by said conveyer, and thresher rolls to receive the grain in a substantially horizontal position, a hook adjacent the end of travel of the grain for the purpose specified, and a cutter lower than the first mentioned cutter and adjacent said hook for the purpose specified, and another conveyer for said grain located between the levels of said cutters.

6. A machine of the class described having coacting threshing rolls to receive unthreshed grain, one of said rolls having longitudinally extending grain receiving pockets, and the other roll having spirally arranged ribs for the purpose specified, a pair of coacting guide rolls beneath the first mentioned rolls, a cutter for the butt ends of the straw located between the planes of the first and second pairs of rolls, and the machine being open from below whereby the cut straw may fall therethrough.

In testimony whereof I affix my signature.
EDWARD J. HALE.
